Specification for Design.

Patented May 4, 1920.

Application filed July 22, 1918. Serial No. 246,191. Term of patent 3½ years.

To all whom it may concern:

Be it known that I, NANCY B. LE DUC, a citizen of the United States, residing at Santa Monica, in the county of Los Angeles and State of California, have invented a new, original, and ornamental Design for Buttons, Brooches, Badges, and Similar Articles, of which the following is a specification, reference being had to the accompanying drawings, forming a part thereof:

Figure 1 is the front elevation on an enlarged scale of a button, Fig. 2 is the side elevation, and Fig. 3 is a perspective view of the reverse side of Fig. 1, showing my new design.

I claim:

The ornamental design for a button, brooch, badge, or similar article, as shown.

NANCY B. LE DUC.
